UNITED STATES PATENT OFFICE.

ORSON DESAIX MUNN, OF SOUTHAMPTON, NEW YORK.

AMUSEMENT APPARATUS.

Application filed June 21, 1922. Serial No. 569,892.

To all whom it may concern:

Be it known that I, ORSON D. MUNN, a citizen of the United States, and a resident of Southampton, in the county of Suffolk and State of New York, have invented a new and Improved Amusement Apparatus, of which the following is a full, clear, and exact description.

This invention relates to amusement apparatus, and has reference more particularly to a competitive game device for use at amusement parks or establishments, or for other like purposes. The invention also relates to an amusement apparatus, which 15 comprises a plurality of targets, each consisting of an inflatable member which serves as the target object, and which, when properly struck, may be burst or deflated.

An object of the invention is to provide 20 a simple and inexpensive amusement apparatus, which may be used competitively or otherwise, which is particularly adapted for service at amusement parks or the like, and which will afford entertainment and 25 means for the practice of skill and accuracy to both young and old.

A further object of the invention is to 30 provide an amusement apparatus consisting of a plurality of targets, in which the number of targets used may be varied as desirable or necessary, in which the targets, when properly struck, instantly burst or deflate, and in which the targets may be 35 very expeditiously and easily replaced at little expense.

With these and other objects in view the 40 invention consists in certain novel features of construction, and combinations and arrangements of parts, as will be more fully hereinafter described and pointed out in the claims.

In the accompanying drawings—

Figure 1 is a vertical section showing an embodiment of my invention;

Figure 2 is a front elevation, partly in vertical section, showing the form of the device illustrated in Figure 1;

Figure 3 is a fragmentary vertical section showing a modified form of my invention; and

Figure 4 is a view similar to Figure 3, showing another modification thereof.

Before proceeding to a more detailed ex-

planation of my invention, it should be clearly understood that, while the amusement apparatus is particularly adapted for use in establishments, such as amusement parks or the like, it is not necessarily limited to such employment, but may be otherwise utilized to afford practice and entertainment. The size of the apparatus too may be varied in accordance with its uses, and any number of target elements, or target elements of any desirable size, may be employed. Primarily, the invention involves the employment of deflatable or burstable target elements, such as small rubber balloons. Such balloons, when inflated, on being touched by a pointed object, instantly burst and deflate, so that the effect of the successful action of the player is very marked. The bursting or deflating of the balloon is often accompanied by a slight explosion, which adds to the entertainment afforded by the device. It will be understood that many of the details of construction form no part of the invention and may be varied in accordance with individual preference or special conditions without departing from the spirit of the invention.

Referring more particularly to the drawings, I have shown in Figures 1 and 2 a form of my invention, in which at the front is disposed the usual counter 10, at the outside of which the players take their positions. Positioned at the rear of the counter and spaced therefrom is a stand 11, which is preferably of stair-shaped cross-section and presents two or more shelves 12 connected by risers 13. The stand 11 is disposed against a rear wall 14. Located under one or more of the shelves 12 are longitudinal pipes 15. These are joined by suitable connections 16 and 17 with a tank or reservoir 30 for compressed air, which is positioned under the stand.

Extending upwardly, through suitable openings provided for the purpose in the corresponding shelf 12, from the pipes 15 are nozzle tubes 18, each having above the shelf 12 a petcock 19. A nozzle 20 is connected to each petcock. This nozzle is preferably a flexible tubing, but which is of such character, that it has a certain degree of rigidity and will maintain a normal substantially vertical position. Mounted upon

each of the nozzles 20 is a balloon element 21. These, it will be understood, may be of different sizes and colors.

When the petcocks 19 are opened, the 5 compressed air from the tank 18 enters the balloon target elements 21, and they may thus be inflated to any desired extent. Back of each line of balloon elements and secured respectively to a riser 13 or the wall 10 15, is a strip 22, which carries a plurality of pins 23, each pin being placed back of, and adjacent to one of the balloon target elements 21. Any suitable projecting device, such as an air gun 24, may be employed 15 in the use of my game apparatus. When such a device is employed, the cork 25, or other projectile from the gun, if the latter is properly aimed, will strike one of the balloon elements 21, and knocking the same 20 against the pin 23, will cause the balloon to be exploded. It will readily be understood that even if the target is struck, but is not struck squarely, it may be thrust to one side without being exploded. This, it 25 will be understood, adds considerably to the skill necessary to the use of the apparatus and to the entertainment afforded thereby. A player may practice alone at the apparatus or two or more players may use the 30 same as competitors.

In the form of the device shown in Figure 3, the air gun or other projecting device is dispensed with. I substitute therefor a flexible member 26 depending from a roof 35 or ceiling 27 over the apparatus. At the lower end of the flexible member is a weighted body 28. In this form of the device the player draws the flexible member rearwardly and releases it, so that it swings as 40 a pendulum, the player endeavoring to strike therewith one of the balloon target elements. If the same is properly struck, it will be exploded in the same manner as above described. In the form of the device shown in 45 Figure 4, I dispense with the pins 23 and provide one or more pins 29 on the weighted member 28. In this form of the device, it will be seen that not only must the target be struck, but the weighted member 28 must 50 strike in such a way that one of the pins will engage the target before the balloon will be exploded.

When a balloon has been exploded, it can very quickly and easily be replaced by the 55 attendant, who simply removes the neck 21^a of the balloon remaining on the nozzle 20, places the new balloon in position, opens the petcock 19, and inflates the balloon to the desired extent. He then shuts off the 60 air and the target is again ready.

I claim:

1. Amusement apparatus, comprising a target consisting of an inflatable member of flexible material having a fixed point of attachment but capable of limited bodily

movement, a pin held in fixed relation to said inflatable member, and means for striking said inflatable member to force the same into contact with said pin.

2. Amusement apparatus, comprising an 70 inflatable member, a pin for bursting said inflatable member, and means within the control of the player for bringing said inflatable member and said pin into contact, said pin having a fixed support, said member 75 having a fixed point of attachment but capable of limited bodily movement.

3. Amusement apparatus, comprising a plurality of inflatable members, means for inflating said members, pins adapted to burst 80 said inflatable members, and means within the control of the players for separately bringing said inflatable members and said pins into contact for the purpose specified, 85 each of said pins having fixed supports, each of said members having a fixed point of attachment but being flexibly mounted so that it has a limited freedom of bodily movement.

4. Amusement apparatus, comprising an 90 inflatable member, a source of compressed air for inflating said member, means for regulating the admission of compressed air to said member, a member capable of bursting said inflatable member, and means within the control of the player for bringing said 95 members into contact, one of said members having a fixed support, the other of said members having a flexible point of attachment permitting limited bodily movement.

5. Amusement apparatus, comprising a 100 fixed nozzle, a source of compressed air, a valved connection between said source and said nozzle, an inflatable member removably mounted upon said nozzle, and means within the control of the player for striking said 105 member with a projectile to burst said inflatable member.

6. Amusement apparatus, comprising a plurality of fixed flexible nozzles, inflatable 110 members removably mounted upon said nozzles, a source of compressed air, valved connections between said source and said nozzles, and means within the control of the player for bursting said inflatable members.

7. Amusement apparatus, comprising a stand, a plurality of inflatable members on said stand, flexible mountings for said inflatable members, pins for bursting said inflatable members, and means within the control of the player for bringing said inflatable members and said pins into contact, said pins and said members being juxtaposed so that they can be brought into contact to 120 burst said members.

8. Amusement apparatus, comprising an 125 inflatable member, means for mounting said inflatable member whereby the same has a fixed point of attachment but limited freedom of movement, a fixed pin near said 130

member, and means controllable by the player for striking said inflatable member to force the same into contact with said pin for the purpose specified.

- 5 9. Amusement apparatus, comprising a stand, a plurality of flexible nozzles on said stand, inflatable members removably mounted upon said nozzles, means for passing compressed air through said nozzles into said 10 inflatable members, fixed pins, each located adjacent to one of said inflatable members, means for predetermining the position of the player with respect to the said stand, and means within the control of the player for 15 striking said inflatable members to force the same into contact with said pins.

10. Amusement apparatus, comprising a counter, a stand rearwardly spaced from said counter, a pipe extending under said 20 counter, a source of compressed air connected with said pipe, a plurality of petcocks connected with said pipe and positioned above said stand, flexible nozzles, each connected with one of said petcocks, removable 25 inflatable members, each mounted upon

one of said nozzles, and fixed pins mounted upon said stand and each adjacent to one of said inflatable members.

11. In an amusement apparatus, a target comprising an oscillatable inflatable member, a fixed support, a flexible connection between the fixed support and the inflatable member, and a pin for bursting said inflatable member and located within the path of oscillation of the inflatable member, and means for impacting said target to oscillate it against the pin. 30 35

12. In an amusement apparatus, a target comprising an inflatable member of flexible material having a fixed point of attachment 40 and oscillatable about its point of attachment, a pin held in fixed relation to said inflatable member and within the path of movement of the inflatable member for bursting the inflatable member when said member is moved into engagement with the pin, and means for oscillating said target 45 into contact with the pin.

ORSON DESAIX MUNN.
